UNITED STATES PATENT OFFICE.

• ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

FLUID-COMPRESSING APPARATUS.

Application filed May 8, 1920. Serial No. 379,717.

To all whom it may concern:

Be it known that I, ROBERT SUCZEK, a citizen of the Czechoslovak Republic, residing in the city and county of Philadelphia, 5 State of Pennsylvania, have invented certain new and useful Improvements in Fluid-Compressing Apparatus, of which the following is a specification.

My invention relates to apparatus for compressing fluid in a plurality of stages by action thereon by ejector apparatus in one stage employing elastic motive fluid, as steam, the condensable fluid discharged by the first stage ejector apparatus being condensed, and the remaining fluid, as air, being acted upon in a later stage by any suitable pump, as ejector apparatus.

My invention resides in apparatus of the character referred to wherein the interstage condensing apparatus is of a structure making possible utilization of independent streams of cooling medium, as water, and more particularly, making possible utilization of streams of cooling medium from different sources, as from the cooling system of a large or main condenser and from the condensate therefrom.

My invention resides further in ejector apparatus combined with structure for condensing the condensable component of the discharge from the ejector passing through tubes subjected from within and without to cooling action; and my invention resides further in such apparatus in which the condensing structure employs independent streams of cooling medium.

My invention resides in the features of construction and combination hereinafter described and claimed.

For an illustration of some of the various forms my invention may take, reference is to be had to the accompanying drawings, in which:

Fig. 1 is a vertical sectional view, partly in elevation, of apparatus embodying my invention.

Fig. 2 is a horizontal sectional view, partly in plan, on the line 2—2 of Fig. 1.

Fig. 3 is a horizontal sectional view, partly in plan, on the line 3—3 of Fig. 1.

Fig. 4 is an elevational view of apparatus

of the character illustrated in Fig. 1 in combination with a main or large condenser.

Fig. 5 is a vertical sectional view, partly in elevation, of a modified structure embodying my invention.

Referring to Fig. 1, E is an ejector, of any suitable type, here indicated as of the tubular type, whose suction port a communicates with the main condenser or other vessel or region from which elastic fluid is to be withdrawn and compressed. Elastic motive fluid, as steam, is supplied to the nozzle structure of the ejector E through the pipe b, controlled by valve c. The diffuser d of the ejector E delivers into the compartment e, Fig. 2, of the condenser structure comprising the shell or body A and the end boxes or chests B, B¹, the aforesaid chamber e being one of three in the box B, as indicated in Fig. 2. These three chambers are formed by the transversely extending partition or wall f and the partition or wall g, the compartment e being formed between the partitions f and g. The compartment h is formed to one side of the partition f, and the chamber or compartment i is formed between the partitions f and g to the left of the latter, Fig. 2. Between the box B and the shell A is the tube sheet j; and between the shell A and the box B¹ is the tube sheet k, compartments m and m¹ being formed within the box B¹ by the partition m². The discharge from the ejector E into the chamber e passes through the vertical tubes n of the upper right hand group, Fig. 2, terminating at their upper ends in the tube sheet j and at their lower ends in the tube sheet k. The discharge passes into the chamber m and thence upwardly through the lower right hand group of tubes n, Fig. 2, into the chamber h, and thence downwardly through the lower left hand group of tubes n into the chamber m¹, and thence upwardly through the upper left hand group of tubes n into the chamber i and outwardly through the discharge conduit o to the suction of any suitable pump, as for example, the second ejector E¹ whose discharge is at p.

Within the shell A between the tube sheets j and k is the partition wall q dividing the

- interior of the shell A into completely independent cooling water passes, the pass to the right of the partition q , Fig. 3, cooling the tubes of the upper and lower right hand groups, while the pass to the left of the partition q cools the tubes of the upper and lower left hand groups, as viewed in Figs. 2 and 3. Intersecting the shell A substantially at right angles to the partition q is the second wall or partition r , whose upper edge forms a tight joint with the tube sheet j , but whose lower edge is spaced from the lower tube sheet k . The cooling water for the right hand pass enters at s , passes around the tubes of the first group downwardly under the edge of the partition r , and upwardly in contact with the tubes of the second group and leaves by the outlet t . Similarly, the cooling water for the left hand pass enters at u , passes downwardly around the tubes of the fourth group around the lower edge of the partition r , and upwardly in contact with the tubes of the third group, and discharges at v .
- Referring to Fig. 4, C represents a main condenser, indicated as a surface condenser, into which condensable fluid, as exhaust steam from a turbine, engine or other source, enters at w and the condensate is delivered into the hot well or condensate outlet x .
- The cooling water for the condenser C is delivered by pump P, driven by any suitable means, as the electric motor M, through the pipe y to the interior of condenser C, and is discharged at the cooling water outlet z . Part of the cooling water delivered by the pump P is diverted through the pipe a^1 , controlled by valve v^2 , to the cooling water inlet u of the auxiliary or interstage condenser A, passes through the condenser A as above described, and is discharged through the outlet v into the pipe b^1 , which may discharge into the main condenser cooling water outlet z .
- Driven by any suitable means, as by the same motor M, is a condensate pump P^1 , which withdraws the condensate from the condensate outlet or hot well x , and all or any suitable fraction of such condensate is delivered by the pump P^1 through the pipe c^1 to the cooling water inlet s of the interstage condenser A, such condensate passing through the interstage condenser A as above described, and discharges at t into a pipe d^1 , which delivers the condensate to the steam boiler feed water heater or pumps, or to any other suitable or desired destination.
- The suction a of the ejector E communicates through a valve e^1 with the air outlet f^1 of the main condenser C. The ejector E therefore withdraws air or uncondensable elastic fluid from the condenser C for maintaining the usual or desired vacuum therein. The withdrawn air in mixture with the

steam or other motive fluid from the ejector E is then discharged into the compartment e of the interstage condenser, the mixture passing through the groups of tubes as above described, and the uncondensed remainder delivered from the connection o to the second stage pump or ejector E^1 .

The mixture from the ejector E in passing through the interstage condenser is first cooled by the condensate from the main condenser C and then is subjected to further cooling by the water delivered by the pump P through the pipe a^1 . Ordinarily, the condensate from the main condenser C will be of higher temperature than its cooling water, and accordingly, in the interstage condenser A the discharge from the ejector E is first brought into heat transfer relation with cooling water of higher temperature and then later with cooling water of lower temperature.

In passing through the groups of tubes in the interstage condenser, the motive fluid or other condensable fluid is more or less completely condensed, the condensate collecting in the chambers m and m^1 in the lower box B^1 . From these the condensate passes off through the pipes g^1 and h^1 controlled, respectively, by valves i^1 and j^1 , these pipes delivering into the pipe p^1 , which delivers into a vacuum trap n^1 , which delivers through the pipe o^1 into the condensate draw-off or hot well x , or to any other suitable destination. When the condensate discharged by the pipe p^1 is delivered into the condensate draw-off or hot well x , it becomes or may become cooling medium for the interstage condenser entering at s and discharged at t .

Referring now to Fig. 5, there is shown an interstage condenser structure of modified form comprising the body or shell D having at its upper and lower ends the tube sheets j and k , in which terminate the vertical tubes n disposed in four groups. Above the upper tube sheet j is a box or chamber F, whose upper wall is formed by the tube sheet p^1 , which also forms the lower wall of the box or chamber B. Similarly, below the tube sheet k is a box or chamber F^1 whose lower wall is the tube sheet q^1 which forms also the upper wall of the lower box or chest B^1 , condensate being drawn off at o^2 , o^2 .

The upper chest F is divided into three compartments r^1 , s^1 and t^1 by the partitions u^1 and v^1 . The lower chest F^1 is divided into two compartments w^1 and x^1 by the partition y^1 . One stream of cooling water enters the shell D through the inlet u , controlled by valve structure V, and leaves at the outlet v , it being understood that the connections u and v may be in the cooling water system of the main condenser, as indicated in Fig. 4. In passing through the

shell D, the cooling water passes downwardly under the edge of the partition a^1 , thence upwardly and across the upper edge of the partition a^2 , thence downwardly and around the lower edge of the partition b^2 , and thence out through the discharge v .

By this action the tubes n conducting the ejector discharge are cooled on their outer surfaces by the cooling water entering at 10 u and discharging at v . The ejector discharge is, however, cooled by the second source of cooling medium which is conducted through the pipes or tubes c^2 terminating in their upper ends in the tube sheet 15 p^1 and in their lower ends in the tube sheet q^1 .

The upper chest B is divided into three compartments, d^2 , e^2 and f^2 , by the partitions g^2 and h^2 ; and the lower chest B' is divided into two compartments i^2 and j^2 20 by the partition k^2 . Cooling water, from any suitable source, for example from the condensate pump P^1 of Fig. 4, is delivered into the inlet s past the flap valve n^2 into the chamber d^2 , thence through the tubes 25 c^2 extending through the first named tubes n , discharging into the chamber i^2 , thence passing upwardly through the second group of tubes c^2 into the chamber e^2 ; thence downwardly through the third group of tubes 30 c^2 into the chamber j^2 ; thence upwardly through the fourth group of tubes c^2 into the chamber f^2 to the discharge outlet t .

Thus, it will be understood that cooling water in two separate and independent 35 streams, as in Fig. 4, or otherwise, passes through the condenser structure, one stream cooling the outside of the tubes n and the second stream cooling the ejector discharge from within the tubes n , the second stream 40 of cooling medium being conducted through tubes disposed within the first named tubes, and the ejector discharge passing through the annular space between the inner and outer tubes.

45 Inasmuch as the amount of condensate from the condenser C, Fig. 4, may vary with variations in load, the amount of condensate delivered through the inlet s , Fig. 5, may vary. To ensure that there shall always be 50 sufficient cooling medium applied to the interstage condenser structure, the flap valve n^2 , responding to the incoming current of condensate through s , controls the valve structure V, so that as the amount of condensate 55 entering at s increases, the valve structure V will be completely closed or moved toward closed position and so diminish the amount of cooling water entering at u ; and vice versa, as the condensate from 60 the main condenser diminishes, the valve V will open or admit more cooling water through the system whose inlet and outlet are u and v .

It will be understood that in the structure 65 of Figs. 1 to 4 inclusive there may be dis-

posed in one cooling water conducting system a control member like member n^2 of Fig. 5 controlling a valve, like valve V, Fig. 5, controlling the cooling medium in the other conducting system.

What I claim is:

1. The combination with an ejector, of condenser structure into which said ejector discharges comprising a plurality of groups of tubes serially related conducting the ejector discharge, and a plurality of independent cooling water passes for cooling different tube groups.

2. The combination with an ejector, of condenser structure into which said ejector discharges comprising a plurality of groups of tubes serially related conducting the ejector discharge, a plurality of independent cooling water passes for cooling different tube groups, and a second ejector connected 85 in series with said first named ejector through said condenser structure.

3. The combination with an ejector, of condenser structure into which it discharges comprising a shell divided into independent 90 compartments, tubes disposed in the different compartments and conducting the ejector discharge in series, and means conducting cooling medium into and from each of said compartments.

4. The combination with an ejector, of condenser structure into which it discharges comprising a shell divided into independent 95 compartments, tubes disposed in the different compartments and conducting the 100 ejector discharge in series, and means conducting cooling medium into and from each of said compartments, each of said compartments having a partition around which the cooling medium passes.

5. The combination with an ejector, of condenser structure into which it discharges comprising a shell divided into independent compartments, tubes disposed in the different compartments and conducting the 110 ejector discharge in series, means conducting cooling medium into and from each of said compartments, and a second ejector receiving the discharge from said first ejector through 115 said condenser structure.

6. The combination with an ejector, of condenser structure into which it discharges comprising a shell divided into independent compartments, tubes disposed in the different compartments and conducting the 120 ejector discharge in series, means conducting cooling medium into and from each of said compartments, each of said compartments having a partition around which the cooling medium passes, and a second ejector receiving the discharge from said first ejector through 125 said condenser structure.

7. The combination with an ejector, of a condenser structure receiving discharge therefrom comprising tubes through which 130

the discharge passes, means for cooling the exterior of said tubes, and tubes within said first named tubes conducting cooling medium.

8. The combination with an ejector, of 5 condenser structure into which said ejector discharges, said condenser structure having a plurality of passes for independent streams of cooling medium, valve structure controlling one of said streams of cooling medium, 10 and means responsive to the amount of cooling medium of another of said streams controlling said valve structure.

9. The combination with an ejector, of 15 condenser structure into which said ejector discharges, said condenser structure having a plurality of passes for independent streams of cooling medium, and means responsive to changes in the quantity of cooling medium in one stream controlling the 20 quantity of cooling medium in another of said streams.

10. The combination with an ejector, of condenser structure into which said ejector discharges comprising four groups of tubes 25 through which the ejector discharge passes in series and alternately in opposite directions, and two cooling medium passes, one for each pair of groups of tubes.

11. The combination with an ejector, of 30 condenser structure comprising a shell, four groups of tubes in said shell, said groups connected in series with each other, a box on one end of said shell divided into three compartments, said ejector discharging into the 35 first of said compartments and through the tubes of the first and second groups into the second compartment, said second compartment discharging through the third and fourth groups of tubes into the third compartment, a box on the other end of said shell divided into two compartments, the first of which receives the discharge from the first group of tubes and discharges into the second group of tubes, and the second 40 compartment receiving discharge from the third group of tubes and discharging into the fourth group of tubes, and two cooling water compartments in said shell, one for cooling the first and second groups of tubes 45 and the other for cooling the third and fourth groups of tubes.

12. The combination with an ejector, of a condenser comprising a shell, groups of tubes in said shell, compartments on opposite ends of said shell themselves divided into compartments and connecting said 50 groups of tubes in series with each other, said ejector discharging into one of said first named compartments and through said tubes, means for delivering cooling medium into and from said shell for cooling the exteriors of said tubes, cooling medium boxes on said first named compartments, said boxes divided into compartments, tubes connecting 55 said boxes and passing through said first

named tubes, and means for delivering cooling medium through said boxes and said last named tubes.

13. The combination with a main condenser, of ejector structure withdrawing 70 fluid therefrom, a second condenser into which said ejector structure discharges, means for supplying said second condenser with a plurality of cooling media one of which is condensate from said main condenser, and means controlled by one of said cooling media controlling another of said cooling media.

14. The combination with a main condenser, of ejector structure withdrawing 80 fluid therefrom, a second condenser into which said ejector structure discharges, means for supplying said second condenser with a plurality of cooling media one of which is condensate from said main condenser, and means controlled by said cooling condensate controlling another of said cooling media.

15. The combination with a main condenser, of ejector structure withdrawing 90 fluid therefrom, a second condenser into which said ejector structure discharges, means for supplying said second condenser with a plurality of cooling media one of which is condensate from said main condenser and another of which is cooling medium of said main condenser, and means controlled by one of said cooling media controlling other of said cooling media.

16. The combination with a main condenser, of ejector structure withdrawing 100 fluid therefrom, a second condenser into which said ejector structure discharges, means for supplying said second condenser with a plurality of cooling media one of which is condensate from said main condenser and another of which is cooling medium of said main condenser, and means controlled by said condensate cooling medium controlling said other cooling medium.

17. The combination with a main condenser, of ejector structure withdrawing 110 fluid therefrom, a second condenser into which said ejector structure discharges, means for supplying said second condenser with a plurality of cooling media one of which is condensate from said main condenser, and means responsive to the rate of supply of one of said cooling media controlling the rate of supply of another of said 115 cooling media.

18. The combination with a main condenser, of ejector structure withdrawing 120 fluid therefrom, a second condenser into which said ejector structure discharges, means for supplying said second condenser with a plurality of cooling media one of which is condensate from said main condenser, and means responsive to the rate of supply of said condensate to said second 125 condenser.

condenser controlling the rate of supply of another of said cooling media to said second condenser.

19. The combination with an ejector, of condenser structure into which said ejector discharges, means for supplying a plurality of cooling media to said condenser structure, and means controlled by one of said cooling media controlling another of said cooling media. 70

20. The combination with an ejector, of condenser structure into which said ejector discharges, means for supplying a plurality of cooling media to said condenser structure, and means responsive to changes in the rate of supply of one of said cooling media controlling the rate of supply of another of said cooling media. 80

21. The combination with an ejector, of condenser structure into which said ejector discharges, means for supplying cooling media of different temperatures to said condenser structure, and means responsive to changes in rate of delivery of the cooling medium of higher temperature controlling the cooling medium of lower temperature. 85

22. The combination with a main condenser, of ejector structure withdrawing fluid therefrom, a second condenser into which said ejector structure discharges comprising a shell divided into independent compartments, tubes disposed in said compartments and conducting the discharge from said ejector structure, means conducting condensate from said main condenser to one of said compartments, and means conducting another cooling medium to another of said compartments. 90

23. The combination with a main condenser, of ejector structure withdrawing fluid therefrom, a second condenser into which said ejector structure discharges comprising a shell divided into independent compartments, tubes disposed in said compartments and conducting the discharge from said ejector structure, means conducting condensate from said main condenser to one of said compartments, and means for conducting a cooling medium of different temperature to another of said compartments. 105

24. The combination with an ejector, of condenser structure into which it discharges comprising a shell, tube sheets at opposite ends of said shell, a partition within said shell extending between said tube sheets and dividing said shell into independent compartments, tubes conducting the discharge from said ejector disposed in said compartments and extending through said shell and through said tube sheets, and means conducting cooling media to said compartments. 110

25. The combination with a condenser shell, of tubes extending therethrough, an ejector discharging through said tubes, means for delivering cooling medium into said shell to cool the exterior of said tubes, and spaced therefrom to form passages for the discharge from said ejector, and means for passing a cooling medium through said second named tubes, and means responsive to 120

said shell to cool the exterior of said tubes, tubes disposed within said first named tubes and spaced therefrom to form passages for the discharge from said ejector, and means for passing a cooling medium through said second named tubes. 130

26. The combination with a condenser shell, of tubes extending therethrough, an ejector discharging through said tubes, means for delivering cooling medium into said shell to cool the exterior of said tubes, tubes disposed within said first named tubes and spaced therefrom to form passages for the discharge from said ejector, and means for passing through said second named tubes a cooling medium of temperature different from the temperature of said first named cooling medium. 135

27. The combination with a condenser shell, of tubes extending therethrough, an ejector discharging through said tubes, means for delivering cooling medium into said shell to cool the exterior of said tubes, tubes disposed within said first named tubes and spaced therefrom to form passages for the discharge from said ejector, and means for passing through said second named tubes a cooling medium whose temperature is higher than the temperature of said first named cooling medium. 140

28. The combination with a condenser shell, of tubes extending therethrough, an ejector discharging through said tubes, means for delivering cooling medium into said shell to cool the exterior of said tubes, tubes disposed within said first named tubes and spaced therefrom to form passages for the discharge from said ejector, means for passing a cooling medium through said second named tubes, and means controlled by one of said cooling media controlling the other cooling medium. 150

29. The combination with a condenser shell, of tubes extending therethrough, an ejector discharging through said tubes, means for delivering cooling medium into said shell to cool the exterior of said tubes, tubes disposed within said first named tubes and spaced therefrom to form passages for discharge from said ejector, means for passing a cooling medium through said second named tubes, and means responsive to changes in rate of delivery of one of said cooling media controlling the rate of delivery of the other cooling medium. 160

30. The combination with a condenser shell, of tubes extending therethrough, an ejector discharging through said tubes, means for delivering cooling medium into said shell to cool the exterior of said tubes, tubes disposed within said first named tubes and spaced therefrom to form passages for the discharge from said ejector, means for passing a cooling medium through said second named tubes, and means responsive to 170

- changes in the rate of delivery of said second named cooling medium controlling the rate of delivery of said first named cooling medium.
- 5 31. The combination with a main condenser, of ejector structure withdrawing fluid therefrom, a second condenser into which said ejector structure discharges comprising tubes, tubes disposed within said first 10 named tubes and spaced therefrom to form passages for the discharge from said ejector, means for delivering cooling medium to the spaces around said first named tubes, and means for conducting cooling medium into said second named tubes, one of said cooling media being the condensate from said main condenser.
- 15 32. The combination with a main condenser, of ejector structure withdrawing fluid therefrom, a second condenser into which said ejector structure discharges comprising tubes, means passing cooling medium around said tubes, tubes disposed within said first named tubes and spaced therefrom to form 20 passages for the discharge from said ejector, and means for delivering condensate from said main condenser into said second named tubes.
- 25 33. The combination with a main condenser, of ejector structure withdrawing fluid therefrom, a second condenser into which said ejector structure discharges comprising tubes, means passing cooling medium around said tubes, tubes disposed within said first 30 named tubes and spaced therefrom to form passages for the discharge from said ejector, and means responsive to the rate of delivery of said condensate to said second named tubes controlling the rate of delivery of said 35 first named cooling medium.
- 40 34. The combination with an ejector, of condenser structure into which said ejector discharges, said condenser structure comprising a plurality of surface condenser units through which said ejector discharge 45 passes in succession, means for passing a cooling medium through one of said condenser units in a direction concurrent with the ejector discharge therethrough, and means for passing a different cooling medium 50 through another of said condenser units in a direction counter to the direction of the ejector discharge therethrough.
- 55 35. The combination with a main condenser, of an ejector withdrawing fluid therefrom, condenser structure into which said ejector discharges, said condenser structure comprising a plurality of surface condenser units through which the ejector discharge 60 passes in succession, means for passing condensate from said main condenser through one of said condenser units in a direction concurrent with the passage of ejector discharge therethrough, and means for passing a different cooling medium through another 65 of said condenser units in a direction counter to the direction of passage of the ejector discharge therethrough.
- 70 36. The combination with a main condenser, of an ejector withdrawing fluid therefrom, condenser structure into which said ejector discharges, said condenser structure comprising a plurality of surface condenser units through which the ejector discharge passes in succession, means for passing condensate from said main condenser through one of said condenser units in a direction concurrent with the passage of ejector discharge therethrough, and means for passing a different cooling medium through another of said condenser units later traversed by the ejector discharge in a direction counter to the direction of passage of the ejector discharge therethrough.
- 75 37. The combination with a main condenser, of an ejector withdrawing fluid therefrom, condenser structure into which said ejector discharges, said condenser structure comprising a shell and a plurality of surface condenser units disposed within said shell and through which the ejector discharge passes in succession, means for cooling one of said condenser units by condensate from said main condenser, and means for cooling another of said condenser units by a different cooling medium.
- 80 38. The combination with a main condenser, of an ejector withdrawing fluid therefrom, condenser structure into which said ejector discharges, said condenser structure comprising a shell and a plurality of surface condenser units disposed within said shell and through which the ejector discharge passes in succession, means for cooling one of said condenser units by condensate from said main condenser, means for cooling another of said condenser units by a different cooling medium, and a second ejector operating upon the uncondensed fluid discharged by the last of said condenser units.
- 85 39. Combined ejector-condenser structure comprising an ejector, a condenser comprising a series of groups of tubes through which said ejector discharges in succession, a condenser shell common to and enclosing said groups of tubes, means for passing a cooling medium through said shell counter-current to a part of said groups of tubes, and means for passing a second cooling medium through said shell independently of said first named medium in contact with another part of said groups of tubes.
- 90 40. Combined ejector-condenser structure comprising an ejector, a condenser comprising a series of groups of tubes through which said ejector discharges in succession, means for directing said discharge in opposite directions in the tube groups which are immediately adjacent each other in the se-

ries of groups, a condenser shell common to and enclosing said groups of tubes, means for passing a cooling medium through said shell counter-current to a part of said groups of tubes, and means for passing a second cooling medium through said shell independently of said first named medium in contact with another part of said groups of tubes.

41. Combined ejector-condenser structure comprising an ejector, a condenser comprising a series of groups of tubes through which said ejector discharges in succession, a condenser shell common to and enclosing said groups of tubes, means for passing a cooling medium through said shell counter-current to a part of said groups of tubes, means for passing a second cooling medium through said shell independently of said first named medium in contact with another part of said groups of tubes, and a second ejector operating upon the discharge from said tubes.

42. The combination with a plurality of ejectors arranged in series, of an interstage condenser comprising a plurality of tubes through which the first stage ejector discharges, and means for subjecting said tubes to a plurality of independent streams of cooling medium. 25

43. The combination with a main condenser, of ejector structure withdrawing fluid therefrom, a second condenser comprising a plurality of tubes through which said ejector structure discharges, means for cooling the ejector discharge while in said tubes by condensate from said main condenser, and 35 means for cooling the ejector discharge while in said tubes by a second cooling medium.

In testimony whereof I have hereunto affixed my signature this 6th day of May, 40
1920.

ROBERT SUCZEK.
